WIRE COILING APPARATUS

James E. Keesee, Jacksonville, Fla., assignor to Mid-
States Steel & Wire Company, Jacksonville, Fla., a
corporation of Indiana

Application February 21, 1955, Serial No. 489,406

8 Claims. (Cl. 242—82)

This invention relates to a wire coiling apparatus and more particularly to apparatus for pulling wire from a galvanizing stand, a wire drawing machine or the like and forming the wire into coils.

It has been the commercial practice for many years to pull the wire from a galvanizing stand, a wire drawing machine or the like onto a rotating block on which the wire is accumulated. The capacity of such blocks have determined the maximum size bundle of coils which can be formed and has necessitated either stopping of the machine to remove the accumulated wire or removal of the wire from the block while it is rotating. Stopping of the machine not only results in loss of time, but may result in spoiling the wire as occurs in a galvanizing stand. Removing the wire while the block is rotating has commonly been practiced in galvanizing stands but is an extremely difficult and dangerous operation.

Coiling machines in which the block is stationary have been proposed with the advantage that the wire may be removed easily from the block in any desired quantity without the necessity of stopping the machine. Such machines have, however, been complicated in the necessary provisions for holding the block stationary and for guiding the wire onto and away from the block.

It is one of the objects of the present invention to provide a wire coiling apparatus in which the block is held stationary by an extremely simple and inexpensive means which serves also to guide the wire away from the block.

According to one feature of the invention, wire coils pass from the block onto an elongated guide rod extending forward and laterally from the block and which may engage a wire receiving means at its outer end to hold the block against rotation.

Another object is to provide an apparatus in which wire is guided onto the block by an arm extending radially from the rotating shaft through which the wire is threaded and which carries a plurality of pulleys at its outer end to direct the wire over the edge of and onto the block.

According to one feature, the pulleys lie in a plane transverse and radial with respect to the shaft to remove any preset in the wire and to give the wire a set tending to make it lie on the block.

A further object is to provide an apparatus in which an adequate number of coils of wire are retained on the block to insure pulling through of the wire without slipping.

In the preferred construction, a number of coils are loosely supported on rods extending from the smaller end of the block with an adjustable lever on the top rod to retard movement of the coils from the block to the rods and with the rod opposite to the guide rod longer than the others to restrict movement of the coils off of the rods onto the guide rod.

The above and other objects and features of the invention will be more readily apparent from the following

2

description when read in connection with the accompanying drawing in which:

Figure 1 is a perspective view of a wire coiling apparatus embodying the invention;

5 Figure 2 is a top plan view with parts omitted; and Figure 3 is a partial section on the line 3—3 of Figure 2.

The wire coiling apparatus of the present invention is adapted to pull wire from a galvanizing stand, a wire drawing machine or other source of wire to be coiled and to form the wire into coils which may in turn be formed into bundles or packages of any desired size for shipment and handling. As shown, the apparatus of the present invention comprises a stand or framework supported on legs 10 which are connected at their upper ends by pillow blocks 11 to support a hollow shaft 12 for rotation about a horizontal axis. The shaft 12 projects beyond the frame or stand 10 at one end to carry a conventional tapered block 13 formed at its larger end with an outwardly extending tapered flange 14. The block 13 is detachably supported on the projecting end of the shaft 12 by means of bearings 15 so that the block is freely rotatable relative to the shaft.

The shaft is adapted to be turned by any suitable power means such as an electric motor 16 supported on the frame. The motor may drive the shaft through a belt 17, an intermediate pulley and sprocket shaft assembly 18 and a sprocket 19. The belt and sprocket in series provide the desired speed reduction from the motor to the shaft so that the shaft will be turned at the correct operating speed.

The wire to be coiled as shown at 21 extends into the end of the shaft 12 and radially outward through an opening 22 in the side of the shaft at the projecting end 35 portion thereof.

The wire extending through the opening 22 may be guided by a guide pulley 23 which extends partially into the opening 22 to receive the wire and direct it radially outward of the shaft.

40 The wire is adapted to be guided and wound onto the block by means of a rotating guiding structure comprising an arm 24 rigidly secured to the projecting end portion of the shaft. The arm is preferably formed in two parts with an angular outer or extension section 25

45 adjustably secured thereto so that the radial effective length of the arm can easily be adjusted to accommodate different sized blocks. The arm section 25 terminates in a lateral flange 26 which carries a pulley support 27 extending diagonally across the edge of the flange 14 on the block. The pulley support 27 carries a plurality of pulleys 28, 29 and 31 which lie in a common plane transverse to the shaft 12 and extending radially with respect to the shaft at an acute angle to the plane of the flange 14. The pulleys are so positioned

50 that the first pulley 28 has its entering edge in radial alignment with the pulley 23 to receive the wire from the pulley 23. The pulley 31 has its outer edge in a plane parallel to the flange 14 and in radial alignment with the side of the flange 14 adjacent to the block and preferably close to the juncture of the flange and the block so that the wire will be properly wound on the block as the arm rotates.

According to one feature of the invention, the wire is threaded over the pulleys 28, 29 and 31 in such a manner that any existing preset in the wire will be removed and the wire will be given a preset tending to make it lie properly on the block. For this purpose the wire is preferably threaded over the pulley 28 under the pulley 29 and over the pulley 31. Bending of the wire as it passes over the pulleys successively will remove any preset therein and since the wire leaves the pulley assembly from the pulley 31 which tends to bend

it in the same direction as the block curvature as will be apparent from Figure 1 the wire will tend to lie correctly on the block. Thus in addition to the function of guiding the wire, the pulleys 28, 29 and 31 serve the purpose of prebending the wire to facilitate its coiling on the block.

Wire wound on the block will be pushed along toward the smaller end thereof by the effect of the block taper and the flange 14 to eventually move off of the smaller end of the block. Since it is necessary to retain several coils of wire on the block to avoid slipping of the wire, the block preferably carries a series of forwardly extending rods 32 which will receive the wire as it passes from the forward smaller end of the block. To restrict passage of the coils from the block proper onto the rods 32, the uppermost rod 32 as seen in Figures 1 and 3 may carry a pivoted lever 33 which can be adjusted to extend upwardly above the surface of the upper rod and which will tend to hold the coils on the block itself. By adjustment of the lever 33 to accommodate different sizes and types of wire the proper number of coils can be retained on the block at all times to insure that there will be no slippage of the wire thereon.

Wire leaving the rods 32 is received and guided by an elongated guide rod 34 having a first section 35 which projects forward from the block near the top thereof, an intermediate section 36 which extends laterally and downwardly away from the block and a tip section 37 which extends downward at a relatively sharp angle from the intermediate section 36 and which may carry a short supporting section 38 projecting vertically downward near its outer end. In use, the supporting section 38 is adapted to be received by a wire receiving member or a part thereof such as a vertical rod 39 extending through the center of a container 41 to hold the outer end of the guide rod against downward movement. With the arm 24 turning clockwise as seen in Figure 1, the strain on the wire tends to turn the block clockwise and this tends to move the outer end of the guide rod downward which is prevented by the supporting member 39. Thus the guide rod serves the dual purposes of guiding the wire coils properly away from the block and to a desired point of collection and of preventing rotation of the block. It will be apparent that coils of wire dropping from the end of the tip section 37 of the guide rod will be received in the container 41 or may be collected on any desired type of stump for further handling.

To prevent the coils of wire from passing too quickly from the rods 32 onto the guide rod 34, the rod 32 lying on the side of the block opposite to the direction in which the guide rod 34 extends is made longer than the other rods 32 as indicated at 32'. Thus the coils after dropping from the other shorter rods 32 onto the guide rod will still be retained against slipping down the guide rod by the longer rod 32' so that the weight or momentum of the coils cannot strip the block. This feature coupled with the adjustable lever 33 makes it readily possible to maintain the desired movement of coils of wire on the block at all times.

In use, the wire may be under relatively high tension and as the arm 24 is rotated by the shaft 12 the wire will be wound around the block against the flange 14 to press the preceding coils or turns forward on the block and to draw the wire through the shaft 12 over the guide pulleys. The guide pulleys will straighten and give the wire a prebend so that it will lie on the block easily with no tendency to coil away from the block or to snarl. As the outer coils are pushed from the end of the block they will be held momentarily by the rods 32 and eventually will drop onto the guide rod 34 to be guided to a collecting point. When the desired quantity of wire has been accumulated at the collecting point, the wire may be cut and the receptacle may be easily removed simply by raising the outer end of

the guide rod 34 without stopping operation of the machine. When a new receptacle is in place, the wire may be collected therein until that receptacle is filled.

In the event coils of different sizes are desired, the block 13 may be replaced easily by a block of a different size. Since the block is supported only by the projecting end of the shaft 12 it can be removed very easily and quickly from the shaft to be replaced by any other desired size of block. The only other adjustment necessary is to adjust the arm section 25 radially on the arm 24 so that the pulleys 28, 29 and 31 will extend properly across the flange of the block relatively close to the periphery thereof.

While one embodiment of the invention has been shown and described in detail, it will be understood that this is for the purpose of illustration only and is not to be taken as a definition of the scope of the invention reference being had for this purpose to the appended claims.

20. What is claimed is:

1. Wire coiling apparatus comprising a tapered block on which wire is to be coiled having a flange at its larger end, a hollow rotatable shaft coaxial with the block and extending from the larger end of the block, a radially extending arm carried by the shaft adjacent to the block, an angular extension on the outer end of the arm extending across the flange on the block, a plurality of pulleys carried by the extension lying in a plane transverse to and extending radially from the shaft, one of the pulleys having one side lying in a radial line from the shaft and a second of the pulleys having an edge lying in a plane parallel to the flange and on the side thereof adjacent to the block, a guide pulley carried by the shaft to guide a wire extending through the shaft radially outward therefrom onto said one of the pulleys, means to rotate the shaft, and means to hold the block against rotation.

2. The construction of claim 1 in which there are three pulleys carried by the extension and the wire is threaded over the two end pulleys and under the center pulley.

3. Wire coiling apparatus comprising a tapered block on which wire is to be coiled having a flange at its larger end, a hollow rotatable shaft coaxial with the block and extending from the larger end of the block, a radially extending arm carried by the shaft adjacent to the block, an angular extension on the outer end of the arm extending across the flange on the block, a plurality of pulleys carried by the extension lying in a plane transverse to and extending radially from the shaft, one of the pulleys having one side lying in a radial line from the shaft and a second of the pulleys having an edge lying in a plane parallel to the flange and on the side thereof adjacent to the block, a guide pulley carried by the shaft to guide a wire extending through the shaft radially outward therefrom onto said one of the pulleys, means to rotate the shaft, a wire guiding rod extending forward and laterally from the smaller end of the block to receive coils of wire from the block and guide them to a collecting point, and means engaging the outer end of the rod to hold it against vertical movement thereby to hold the block against rotation.

4. Wire coiling apparatus comprising a tapered block on which wire is to be coiled having a flange at its larger end, a hollow rotatable shaft coaxial with the block and extending from the larger end of the block, a radially extending arm carried by the shaft adjacent to the block, an angular extension on the outer end of the arm extending across the flange on the block, a plurality of pulleys carried by the extension lying in a plane transverse to and extending radially from the shaft, one of the pulleys having one side lying in a radial line from the shaft and a second of the pulleys having an edge lying in a plane parallel to the flange and on the side thereof adjacent to the block, a guide pulley carried by the shaft to guide a wire extending through the shaft radially outward there-

from onto said one of the pulleys, means to rotate the shaft, a wire guiding rod extending forward and laterally from the smaller end of the block to receive coils of wire from the block and guide them to a collecting point, and an upright wire collecting device including a part engaging the outer end of the guiding rod to hold it against downward movement thereby to hold the block against rotation.

5. Wire coiling apparatus comprising a horizontal hollow rotatable shaft, a frame supporting the shaft for rotation, a tapered block rotatably mounted on one end of the shaft with its larger end toward the shaft and having a flange at its larger end, an arm extending radially from the shaft adjacent to the block, an angular extension at the outer end of the arm extending across the flange, a plurality of pulleys carried by the extension lying in a plane transverse to and extending radially from the shaft, one of the pulleys having one side lying in a radial line from the shaft and a second of the pulleys having an edge lying in a plane parallel to the flange and on the side thereof adjacent to the block, a guide pulley carried by the shaft to guide a wire extending therethrough radially outward therefrom onto said one of the pulleys, means to rotate the shaft, an elongated wire guiding rod projecting forwardly and laterally from the smaller end of the block, and means engaging the outer end of the guiding rod to hold it against vertical movement.

6. Wire coiling apparatus comprising a hollow rotatable shaft having a lateral opening near one end through which a wire may extend, a tapered block having a flange at its larger end, means mounting the block for free rotation with its larger flanged end adjacent to said one end of the shaft, guide means carried by the shaft to direct wire extending from the shaft over the flange on the block to coil the wire on the block as the shaft turns relative to the block, an elongated guide rod extending forwardly and laterally from the smaller end of the block to receive coils of wire from the block and means en-

5 gaging the end of the guide rod to hold it against vertical movement thereby to hold the block against rotation.

7. Wire coiling apparatus comprising a hollow rotatable shaft having a lateral opening near one end through which a wire may extend, a tapered block having a flange at its larger end, means mounting the block for free rotation with its larger flanged end adjacent to said one end of the shaft, guide means carried by the shaft to direct wire extending from the shaft over the flange on the block to coil the wire on the block as the shaft turns relative to the block, a plurality of short rods extending outward from the smaller end of the block and spaced around the periphery thereof loosely to hold a series of coils on the block, and an adjustable lever carried by the uppermost of the rods to engage the outermost coil on the block and restrict passage of the coils from the block onto the rods.

8. Wire coiling apparatus comprising a hollow rotatable shaft having a lateral opening near one end through which a wire may extend, a tapered block having a flange at its larger end, means mounting the block for free rotation with its larger flanged end adjacent to said one end of the shaft, guide means carried by the shaft to direct wire extending from the shaft over the flange on the block to coil the wire on the block as the shaft turns relative to the block, a plurality of short rods extending outward from the smaller end of the block and spaced around the periphery thereof loosely to hold a series of coils on the block, and a guide rod extending laterally from the smaller end of the block to receive coils from the rods and direct them laterally away from the block, the rod at the side of the block opposite to that of the guide rod being longer than the other rods to retain the coils longer on the rods without tangling thereof.
